(57) **CLAIM**

The ornamental design for a sterile medical tool caddy, as shown and described.

DESCRIPTION

FIG. 1 is a rear perspective view of a sterile medical tool caddy.

FIG. 2 is a front view thereof;

FIG. 3 is a plan back view thereof;

FIG. 4 is a left side view thereof;

FIG. 5 is a right side view thereof;

FIG. 6 is a top view thereof; and,

FIG. 7 is a bottom view thereof.

The broken lines depict portions of the sterile medical tool caddy that form no part of the claim.
